ALFRED WOODHOUSE,

A. L. Woodhouse

UNITED STATES PATENT OFFICE.

ALFRED WOODHOUSE, OF LONDON, ENGLAND.

APPARATUS FOR THE AMALGAMATION OF GOLD.

SPECIFICATION forming part of Letters Patent No. 416,390, dated December 3, 1889.

Application filed March 11, 1889. Serial No. 302,843. (No model.) Patented in England April 18, 1887, No. 5,627.

To all whom it may concern:

Be it known that I, ALFRED WOODHOUSE, a resident of London, England, and a subject of the Queen of the United Kingdom of 5 Great Britain and Ireland, have invented an Improvement in Apparatus for the Amalgamation of Gold, (patented to me in Great Britain and Ireland under No. 5,627, and date April 18, 1887,) of which the following is a 10 specification.

My invention relates to apparatus for effecting the amalgamation of gold from its crushed ores, and is designed to effect that amalgamation more perfectly by direct contact without mechanical agitation.

My apparatus comprises an "amalgamating-box" of novel construction, which is preferably combined in series with certain other devices, as hereinafter described.

20 In order that my invention may be better understood, I now proceed to describe the same in relation to the drawings hereunto annexed, reference being had to the letters marked thereon.

25 Figure 1 is a general sectional elevation of a complete gold-amalgamating mill. Fig. 2 is an enlarged sectional elevation of my improved amalgamating-box on the line A B. Fig. 3 is a part sectional plan of the same on 30 the line C D. Fig. 4 shows in detail the baffle-plates with check-gates.

The ore is first to be crushed or reduced to fine powder by any known mill or pulverizer *a*, and the crushed products are, after admixture with mercury, washed by a suitable stream of water to effect a uniform delivery into a canister or box *b*, provided with a perforated bottom, which, if of copper, is either amalgamated in the usual way or electro-40 plated with silver. The crushed ore is thence delivered upon a dropping amalgamator or silvered copper table *c* with return incline and provided with a retaining-lip at the lower edge. Thence the amalgamated ore is dis-45 charged over the usual known "riffles" with or without splash or guide boards and inclined plane or planes *d d*, amalgamated or silvered, a continuous plane formed with a corrugated surface being preferred. The 50 corrugations may be either ordinary rounded waves, or with sharp apices, or with serrations,

to more effectively catch the amalgamated gold, the corrugations being transverse to the flow of the ore. I find corrugations two or three inches apart with a quarter-inch 55 pitch give the best results, and find that they clear themselves if given twice the slope required by a flat plate.

In combination with these more or less known devices I use an amalgamating-box or 60 divided chamber *e*, of suitable material—such as copper, amalgamated or silvered on both sides. I construct this chamber or box as follows, and as shown in detail in Figs. 2 and 3. The box or chamber is made with a 65 wooden frame and is divided by a series of vertical plates *f f*, which are placed transversely to the flow of the amalgamated ore, and which are conveniently dropped into corresponding saw-cuts in the wooden frame. 70 They are provided with orifices *g g* with side projecting faces or wings *h h*, the orifices being so arranged as to flank and baffle each other in the successive check-gates, being placed about two to three inches apart. I 75 make these orifices as follows: The strips are about three inches deep. I cut slits in the form of a T, two inches high and two inches wide and four inches apart from center to center, and bend back the wings until they 80 present an opening about one-half an inch in width, as in Fig. 4. I may further use any suitable number of riffles among or beyond these check-gates, if required. A slope must be given to this box, so that the fluid rises 85 above the top of the T-cut and yet does not rise to overflow the strip.

By the combination of all or several of these devices I seek to effect as perfect an amalgamation as possible of the pulverized 90 gold ore by direct contact with the mercury as it flows through the said apparatus without mechanical agitation.

Having now particularly described and ascertained the nature of my said invention 95 and in what manner the same is to be performed, I declare that what I claim is—

1. In an amalgamating apparatus for separating gold from pulverized ore, the combination, in series, of the canister *b*, the dropping-amalgamator *c*, suitable riffles *d*, and an amalgamating-box *e*, the latter divided by a

series of vertical plates, which are transverse to the flow of the ore and are provided at bottom with orifices which alternate in successive plates, and with lateral wings on the 5 delivery side at each orifice, substantially as hereinbefore specified.

2. The within-described amalgamating-box, composed of an inclined frame in the form of a shallow trough, and a series of vertical 10 plates which are transverse to the flow of the ore and are provided at bottom with orifices,

those of one plate alternating with those of the next, and having lateral wings on the delivery side at each orifice, substantially as hereinbefore specified.

In testimony whereof I have signed my name to this specification in the presence of two subscribing witnesses.

ALFRED WOODHOUSE.
